COMBINED CAN OPENER AND CLOSURE
REMOVER FOR BOTTLES AND JARS

Winfield R. MacKeeby, 501 Dorset Road,
Devon, Pa. 19333

Filed Apr. 25, 1968, Ser. No. 11,612

Term of patent 14 years

Int. Cl. D8—02

U.S. Cl. D44—29

Fig. 1.

Fig. 2.

Fig. 3.

Fig. 4.

Fig. 5.

Fig. 6.

Fig. 7.

Fig. 8.

FIG. 1 is a top plan view of a combined can opener and closure remover for bottles and jars showing my new design in an open condition;

FIG. 2 is a bottom plan view;

FIG. 3 is an elevational view from the bottom of FIG. 1;

FIG. 4 is an elevational view from the top of FIG. 1;

FIG. 5 is an elevational view from the right of FIG. 1;

FIG. 6 is an elevational view from the left of FIG. 1;

FIG. 7 is a top plan view of the article in closed condition; and

FIG. 8 is a bottom plan view thereof.

I claim:

The ornamental design for a combined can opener and closure remover for bottles and jars, as shown and described.
